UNITED STATES PATENT OFFICE.

THOMAS S. SMITH, OF TOONER'S STATION, TENNESSEE, ASSIGNOR OF ONE-HALF HIS RIGHT TO JOHN P. GILDERSLEEVE, OF NIVERVILLE, NEW YORK, AND JOHN W. BLAKE, OF SPRINGFIELD, MASSACHUSETTS.

IMPROVEMENT IN COTTON-PRESSES.

Specification forming part of Letters Patent No. 141,393, dated July 29, 1873; application filed July 9, 1873.

To all whom it may concern:

Be it known that I, THOMAS S. SMITH, of Tooner's Station, in the county of Hardeman and State of Tennessee, have invented a new and valuable Improvement in Cotton-Presses; and I do hereby declare that the following is a full, clear, and exact description of the construction and operation of the same, reference being had to the annexed drawings making a part of this specification, and to the letters and figures of reference marked thereon.

Figure 1 of the drawings is a representation of a vertical section of my invention.

My invention has relation to cotton-presses; and consists in the hereinafter-described construction and novel arrangement of devices for raising and lowering the press-follower.

Referring to the drawings, A represents the press-box, supported by the frame B. C is the press-follower, adapted to exert pressure by rising from the bottom of the box A, which is open. D designates two levers, pivoted to the under side of the follower, and fulcrumed between standards d, secured to transverse movable shafts, d¹. To the end of each lever is attached a rope, d². These ropes pass around a windlass or drum, E, the shaft of which holds a grooved pulley-wheel, F, and a ratchet, F'. A rope, g, is secured to and is wound around said pulley-wheel, and thence passes to an upright windlass, G.

By turning this windlass so as to wind the

rope g around it, the windlass e is so turned as to wind up the ropes d², and to draw the lower ends of the levers D toward each other, thereby elevating the press-follower and exerting a very strong pressure upon it. By unwinding the rope g from its windlass, the levers are allowed to spread apart, and the follower to descend.

A dog, H, engages with the ratchet F, and causes the follower to be retained at any desirable position.

As the levers D move, the standards d and shafts d¹ move with them, giving said levers greater scope in their movements, and lessening the amount of power required to operate them.

What I claim as my invention, and desire to secure by Letters Patent, is—

The cotton-press herein described, consisting of the levers D, pivoted to the under side of the movable follower C, toggle-arms d d attached to shafts d¹ and levers D, pulley F provided with the windlass E and ratchet-wheel F', windlass G, and ropes d², all arranged and operating in the manner set forth.

In testimony that I claim the above I have hereunto subscribed my name in the presence of two witnesses.

THOMAS S. SMITH.
